United States Patent Office

Des. 181,711
Patented Dec. 17, 1957

181,711

AMPHIBIOUS AUTOMOBILE

Arthur J. Di Stasi, Trenton, N. J.

Application December 18, 1956, Serial No. 44,236

Term of patent 14 years

(Cl. D14—3)

Figure 1 is a side elevation of an amphibious automobile embodying my new design, the opposite side of which is substantially similar to that shown;

I claim:

The ornamental design for an amphibious automobile, substantially as shown and described.
